EXPLOSIVE COMPOSITION AND PROCESS
FOR MAKING SAME

Elbert Elbridge De Maris, Woodbury, Charles Donald Forrest, Westville, and George Adelbert Noddin, Mantua, N.J., assignors to E. I. du Pont de Nemours and Company, Wilmington, Del., a corporation of Delaware
No Drawing. Filed June 20, 1961, Ser. No. 118,260
5 Claims. (Cl. 149—19)

This invention relates to a high explosive composition in pellet form having high thermal stability and high compressive strength.

In perforating oil wells at elevated temperatures, charges of pressed cyclonite (RDX) supported in metal or plastic containers have been used. The pressed cyclonite, besides requiring a supporting container because of lack of compressive strength, also lacks the requisite thermal stability in wells where the temperature exceeds 350° F. A need exists for a high explosive pellet which has high degree of cohesion and compressive strength, i.e., needs no metal or plastic supporting container, and is stable at temperatures in the vicinity of 500° F.

In accordance with this invention, high explosive pellets having a compressive strength of at least 10,000 p.s.i. and stable at a temperature of 500° F. are provided which contain from 80 to 95 parts by weight of tetrinitrobenzo-1,3a,4,6a-tetraazapentalene and from 20 to 5 parts by weight of a binder which comprises an epoxy resin having more than one epoxy group per molecule and a curing agent therefor which may be pyromellitic dianhydride (PMDA) or certain PMDA-polyhydric alcohol adduct compounds, the curing agent being present in an amount sufficient to provide from 0.5 to 1.0 anhydride group for each epoxy group of the epoxy resin.

The tetrinitrobenzo-1,3a,4,6a-tetraazapentalene explosive used in my invention and a suitable process for its preparation are described in detail in copending application Serial No. 116,922, filed June 8, 1961, in the name of R. A. Carboni and assigned to the present assignee. This compound may be represented structurally as follows:

(I)

Tetrinitrobenzo-1,3a,4,6a-tetraazapentalene has two nitro group substituents in any position on each benzene ring. There will obviously be numerous isomers of tetrinitrobenzo-1,3a,4,6a-tetraazapentalene based upon the position of the nitro groups alone, which may be in ortho, meta, or para relationship on each individual ring. The existence of several of these isomers has been confirmed by infrared analysis, and all of the possible isomers in this regard are believed to be present to a greater or lesser extent in a synthesis product. For purposes of the present invention, there is no material distinction between any such isomers, i.e., the explosive and thermal properties of these isomers appear to be quite similar and the explosive pellet of the present invention may in-

2

clude any of these isomers individually or may be a combination of any such isomers in any proportion. Actually, separation of the isomers is very difficult because of the similarity in their properties, and synthesis of the composition would normally result in a mixture of isomers, as noted above. This is perfectly satisfactory insofar as the explosive pellets of the present invention are concerned and the product may be used directly in this form.

10 The PMDA-polyhydric alcohol adduct compounds, which may be used in accordance with the invention as the curing agent for the epoxy resin, are described as a class in detail in copending application Serial No. 840,251, filed September 16, 1959, in the name of T. J. Hyde along with a suitable method of preparation. These compounds may be represented structurally as follows:

25 wherein “—O—R—O—” represents the nucleus of the polyhydric alcohol, i.e., the alcohol minus two of its hydroxyl hydrogen atoms. These materials are prepared by condensing at least one and one-half moles of PMDA with one mole of any of a wide variety of polyhydric alcohols, including such alcohols as aliphatic glycols, such as 1,4-butanediol, ethylene glycol, neopentyl glycol, and the like; ether glycols such as diethylene ether glycol, polyoxyethylene glycol, polyoxypropylene glycol, and the like; block-copolymer glycols formed by the successive reaction of the corresponding glycols with ethylene oxide and propylene oxide, or the like; cyclic glycols; polyols, such as glycerol, 1,2,6-hexanetriol and the like; diesters having terminal hydroxyl groups, such as bis(β-hydroxyethyl) isophthalate and terephthalate; polyester materials 30 having terminal hydroxyl groups, such as polyethylene terephthalate, and natural products such as soybean oil and sugar, etc., containing two or more hydroxyl functions per molecule. Any and all such condensation products are suitable in the invention as the curing agent for the 35 epoxy resin as is PMDA itself.

40 Epoxy resins suitable in the invention are those having more than one epoxy group per molecule, i.e., an epoxy equivalency greater than one. For example, the 45 epoxy resins may be a glycidyl polyether of a polyhydric 50 phenol or alcohol, an alicyclic diepoxyde resin, an aliphatic polyepoxide resin, etc.

Although the amount of the epoxy resin-curing agent mixture combined with the tetrinitrobenzo-1,3a,4,6a-tetraazapentalene may range between 20 and 5 parts by 55 weight, for 80 to 95 parts by weight of tetrinitrobenzo-1,3a,4,6a-tetraazapentalene, the preferred amount of epoxy resin-curing agent mixture is 10 parts by weight for 90 parts of tetrinitrobenzo-1,3a,4,6a-tetraazapentalene.

60 The preferred amount of dianhydride compound is that which provides 0.8 anhydride groups for each epoxide group, although as stated previously, a range of 0.5 to 1.0 anhydride group per epoxide group may be used.

65 The manner of mixing the tetrinitrobenzo-1,3a,4,6a-tetraazapentalene with the epoxy resin-curing agent mix-

ture is not critical. For ease in handling, the epoxy resin, which may be a viscous liquid or a low-melting solid, may be dissolved in or diluted with a convenient solvent, e.g., acetone, and then combined with the curing agent which also preferably is in solution form. When a PMDA-polyhydric alcohol adduct is used as the curing agent, the condensation of the PMDA and the alcohol may conveniently be carried out in the presence of a reaction medium solvent, such as acetone, methyl ethyl ketone, methyl isobutyl ketone, tertiarybutyl alcohol, and the like. This resulting solution of the condensation product, i.e., the adduct, may be mixed directly with the epoxy resin or a solution of the epoxy resin in a solvent, such as acetone. Mixtures of solvents may also be used, e.g., acetone and methyl ethyl ketone. The solvent solution, 15 of epoxy resin and the curing agent may then be mixed with the solid tetranitrodibenzo-1,3a,4,6a-tetraazapentale. The amount of solvent used is not critical. However, the use of large amounts of solvent affords no economic advantage because of the need to remove the solvent to form a free-flowing powder. The solvent may be removed from the explosive-epoxy resin-curing agent mixture by conventional means, e.g., vacuum drying, providing the temperature is maintained below the temperature at which significant curing takes place (generally 20 below about 50° F.).

The powder mixture resulting from the removal of the solvent may be compressed into pellets immediately or, if desired, may be stored at low temperature, e.g., 0° F. for extended periods to inhibit the curing reaction until the time desired. Pellets from both the powder mixture compressed immediately after mixing and that compressed after storage at 0° F. exhibited approximately the same compressive strength upon being cured under identical conditions. Thus, in certain cases, it may be advantageous to prepare the powder mixture beforehand and store the mixture until the time it is desirable to form pellets.

In order to provide the requisite density and compressive strength, the amount of compressive pressure required to form the pellets will depend upon the amount of binder used. When the weight percent of binder used is low, e.g., approximately 5%, a compressive pressure of approximately 50,000 p.s.i. is generally used to obtain a pellet, which when cured, will have compressive strength of at least about 10,000 p.s.i. When the weight percent of binder used is high, e.g., 15%, a compressive pressure as low as 15,000 p.s.i. is suitable to obtain a pellet, which when cured, will have a compressive strength of at least 10,000 p.s.i. Of course, higher compressive pressures, if desired, may be applied without any detrimental effect; however, no economic advantage entails therefrom. Generally, when a composition containing the preferred amount of binder, 10% by weight, is to be pelleted, the compressive pressure applied will be at least 35,000 p.s.i.

The temperature at which the pellets are cured may range from room temperature to about 400° F. Of course, curing at room temperature requires a period of several days to effect substantial crosslinking; whereas, at elevated temperatures, e.g., 400° F., substantial crosslinking occurs in several hours. The optimum curing schedule (time-temperature relationship) has been found to be about 10 hours at 400° F.

In the following examples which illustrate the invention, a Dillon Model L Universal Testing Machine with a compression cage, 0-10,000-pound dynamometer, and powered with an air motor was used to compress the pellets. The compressive strength was determined according to ASTM Test Method D695-54, as described in ASTM Standards, 1958 edition, Part 9, pages 244-251.

In all of the ensuing examples, the epoxy resin employed was a liquid epoxy resin which had an approximate molecular weight of 390, an epoxide value of 0.52 per 100 grams, and a viscosity, at 25° C., of about 100 to about 160 poises. This resin is a glycidyl polyether of a

dihydric phenol formed by the condensation of epichlorohydrin and 4,4'-isopropylidene diphenol, and is available commercially as "Epon" 828, manufactured by Shell Chemical Company.

5 The PMDA-polyhydric alcohol adduct used as a curing agent for the epoxy resin in the examples, unless otherwise indicated, was prepared by refluxing, under a blanket of dry nitrogen for a few hours, a mixture of 30 parts of PMDA, 25 parts of 2,2-bis[4-(2-hydroxyethoxy)phenyl]propane (which is available commercially as Dow Resin 10 X-2635 manufactured by the Dow Chemical Company), and 45 parts of methyl ethyl ketone as a solvent. The molar ratio of PMDA/alcohol was 2/1. The adduct obtained may be represented as follows:

The parts in the examples are parts by weight.

Example 1

A free-flowing powder was prepared by mixing 36 25 parts of particulate tetranitrodibenzo-1,3a,4,6a-tetraazapentale having an average particle size of about 100 microns with a premixed solution of 2.2 parts of the 30 epoxy resin dissolved in 27 parts of acetone and 3.3 parts of the PMDA-polyhydric alcohol adduct solution (containing 1.8 parts of solids). This combination provided 35 0.8 anhydride group for each epoxy group. The mixture was vacuum dried at a temperature below 50° C. to remove all traces of acetone and ketone.

Two and one-half-part portions of the thus prepared 35 powder were immediately compressed without application of heat in a cylindrical mold approximately 1/2 inch in diameter and 1/2 inch in length under 40,000 p.s.i. pressure for a 30-second dwell time. The pellets were cured 40 at 400° F. for a period of 18 hours. The cured pellets had a density of approximately 1.63 g./cc. and representative pellets exhibited compressive strengths of approximately 13,000 p.s.i.

The detonation velocity of the pellet was 7,200 m./sec. When small quantities of the uncured and cured explosive 45 composition were subjected to the standard impact sensitivity test, the explosive drop tests were, respectively, 51 and 55 inches. In the impact sensitivity tests, a 5-kilogram weight is dropped upon the explosive from various heights. Drop test results are reported in inches which correspond to the distance which the weight must fall to effect initiation. Those explosives initiated only when the weight falls considerable distances, e.g., 40 to 56 inches, are of low impact sensitiveness.

When a portion of the molding powder was allowed to 55 remain standing for 1 day before being compressed into a pellet and cured according to the procedure described above, the pellets had a density of 1.61 g./cc. and a compressive strength of 11,500 p.s.i.

When a small portion of the molding powder was allowed to 60 remain standing 6 days before being compressed and cured according to the procedure described above, the pellets had a density of 1.61 g./cc. and a compressive strength of 10,500 p.s.i.

Example 2

A free-flowing powder was prepared by mixing 54 parts 65 of particulate tetranitrodibenzo-1,3a,4,6a-tetraazapentale having an average particle size of about 100 microns with a premixed solution of 4.6 parts of the epoxy resin and 1.4 parts of PMDA in 40 parts of acetone. This 70 combination provided 0.55 anhydride group for each epoxy group. The mixture, while being stirred in a three-necked 500-milliliter flask, was vacuum dried. A portion of the powder mixture was refrigerated at 0° F. overnight and then compressed according to the procedure described in 75

5

Example 1. Pellets cured at 400° F. for a period of 4 hours had a density of 1.62 g./cc. and a compressive strength of 10,500 p.s.i. Pellets cured at 400° F. for a period of 8 hours had a density of 1.62 g./cc. and a compressive strength of 11,500 p.s.i. Pellets cured at 400° F. for a period of 18 hours had a compressive strength of 11,000 p.s.i. and lost only 0.4% weight.

A portion of the molding powder was stored at 0° F. for a period of 13 days and then compressed into pellets according to the procedure described in Example 1. Pellets cured at 400° F. for a period of 18 hours had a compressive strength of 11,000 p.s.i.

Example 3

The procedure of Example 2 was used for preparing a free-flowing powder except that 36 parts of particulate tetrabenzodibenz-1,3a,4,6a-tetraazapentalene, 2.8 parts of the epoxy resin, and 1.2 parts of PMDA were used. This combination provided 0.8 anhydride group for each epoxide group. A portion of the mixture was immediately compressed as described in Example 1. Pellets cured at room temperature for a period of 10 days had a density of 1.66 g./cc. and a compressive strength of 12,000 p.s.i. When these pellets were cured further at 400° F. for a period of 18 hours, the density decreased to 1.61 g./cc. and the compressive strength was only slightly lowered to 11,500 p.s.i.

When the above cured pellets were heated in an oil bath at gradually increasing temperatures to determine the thermal stability, the pellets remained stable, that is did not show evidence of internal heating until a temperature of 520° F. was attained and only fumed off (did not detonate) when the temperature reached 550° F.

Example 4

A free-flowing powder was prepared by mixing 127.5 parts of particulate tetrabenzodibenz-1,3a,4,6a-tetraazapentalene having an average particle size of about 100 microns with a premixed solution of 15.6 parts of the epoxy resin and 6.9 parts of PMDA in 70-80 parts of acetone. This combination provided 0.8 anhydride group for each epoxy group. The acetone was evaporated by heating the stirred mixture on a steam bath until a friable solid resulted. The solids then were screened through a silk cloth to eliminate any lumps and vacuum dried at 50° C. for 1 hour.

Two and one-half-part portions of the thus prepared free-flowing powder were immediately compressed without application of heat in a cylindrical mold approximately 1/2 inch in diameter and 1/2 inch in length for a 30-second dwell time. The characteristics of pellets compressed at various pressures and cured at 400° F. for 16 hours are given in the following table.

Compre- sion Pres- sure (p.s.i.)	Density of Cured Pel- lets (g./cc.)	Compre- sive Strength (p.s.i.)
15,000	1.50	11,000
20,000	1.51	11,750
30,000	1.52	12,500
40,000	1.53	13,000
50,000	1.54	13,000

Pellets prepared and cured as above were unaffected by subjection to a temperature of 500° F. for a period of 18 hours.

Pellets prepared and cured as above were initiated by an electric blasting cap containing 3 grains of an igniter mix (50/25/25 parts by weight of smokeless powder/potassium perchlorate/and the lead salt of dinitro-o-cresol, respectively), 3 grains of lead azide as a primer charge, and 3 grains of pentaerythritol tetranitrate as the base charge or, alternatively, a thin-bottomed aluminum sheathed cap containing an igniter bead (75/20/5 parts by weight of the lead salt of dinitro-o-cresol/potassium

6

perchlorate/selenium, respectively), 2 grains of lead azide as a primer charge, and 2 grains of pentaerythritol tetranitrate as the base charge. The detonation velocity of the pellet was 6,650 meters per second.

Example 5

A free-flowing powder was prepared as described in Example 4, except that 95 parts of tetrabenzodibenz-1,3a,4,6a-tetraazapentalene, 1.5 parts of PMDA, 3.5 parts of the epoxy resin, and 32 parts of acetone were used. Pellets compressed at 50,000 p.s.i. and cured at 400° F. for 16 hours had a compressive strength of 10,000 p.s.i. and a density of 1.62 g./cc.

While the invention has been described and illustrated in the foregoing specification, it will be readily apparent to those skilled in the art that many variations may be made in the compositions and procedures disclosed without departing from the spirit or scope of the invention. It is intended, therefore, to be limited only by the following claims.

We claim:

1. A new explosive composition comprising a mass of hard, tough, compact, thermally-stable pellets containing from 80 to 95 parts by weight of:

and from 20-5 parts by weight of an epoxy resin having more than one epoxide group per molecule cured with a dianhydride compound selected from the group consisting of pyromellitic dianhydride and the condensation products of pyromellitic dianhydride and polyhydric alcohols in a molar ratio of at least 1.5:1, said dianhydride compound providing from 0.5-1.0 anhydride group for each epoxy group of the epoxy resin.

2. A process for preparing a new explosive composition which comprises pelletizing a free-flowing mixture of from 80 to 95 parts by weight of:

and from 20 to 5 parts by weight of a mixture of an epoxy resin having more than one epoxide group per molecule and a dianhydride curing agent for the epoxy resin selected from the group consisting of pyromellitic dianhydride and the condensation products of pyromellitic dianhydride and polyhydric alcohols in a molar ratio of at least 1.5:1, the amount of dianhydride curing agent being sufficient to provide from 0.5 to 1.0 anhydride group for each epoxy group of the epoxy resin, and curing the epoxy resin with the said curing agent.

3. A process as in claim 2 wherein the curing is effected by heating the pellets to a temperature within the range of about 60 to 400° F.

4. A process for preparing a novel explosive composition which comprises mixing from 80 to 95 parts by weight of:

with an organic solvent solution of from 20 to 5 parts by weight of a mixture of an epoxy resin having more than one epoxide group per molecule and a dianhydride curing agent for the epoxy resin selected from the group

consisting of pyromellitic dianhydride and the condensation products of pyromellitic dianhydride and polyhydric alcohols in a molar ratio of at least 1.5:1, the amount of dianhydride curing agent being sufficient to provide from 0.5 to 1.0 anhydride group for each epoxy group of the epoxy resin, removing the organic solvent at a temperature below about 50° F. to obtain a free-flowing powder,

pelletizing said powder, and thereafter curing the epoxy resin component of the powder with the said curing agent.

5 5. A process as in claim 4 wherein said curing is effected by exposing the pellets to a temperature within the range of about 60 to 400° F.
